CLASP FOR BRACELETS

Gale A. Rounds, Rapid City, S. Dak., assignor of
one-half to Ivan E. Landstrom, Rapid City,
S. Dak.

Application February 16, 1949, Serial No. 76,829

5 Claims. (Cl. 24—71)

1

My invention relates to clasps for bracelets, wrist watch straps, etc., and has for an object to provide a clasp which may be positively locked in closed position.

Another object of the invention resides in providing a clasp which requires manual manipulation to open and which automatically becomes latched upon closing of the bracelet.

A still further object of the invention resides in constructing the clasp with a body having a web and spaced flanges issuing outwardly therefrom and with an inner link pivoted to one end of the body and with an outer link pivoted to the inner link and in providing latching means including a catch extending through one of the flanges.

A feature of the invention resides in providing the outer link with flanges adapted to be disposed adjacent the flanges of the body and in providing the body flange with a closed slot and the link flange with an open-ended slot adapted to register with a portion of the closed slot and in which the catch is movable.

Another object of the invention resides in constructing the closed slot in the form of a bayonet with a longitudinal leg and a transverse leg and forming a shoulder therebetween, and in arranging the open ended slot to register with the longitudinal leg of the closed slot.

A still further object of the invention resides in providing resilient means for urging the catch against said shoulder and toward the end of the longitudinal leg.

An object of the invention resides in providing a lug on the outer link adapted to engage said catch and move the same out of the transverse leg and into the longitudinal leg when the parts are brought into closing position to cause the catch to enter the open-ended slot and latch the parts in closed position.

Another object of the invention resides in constructing the latch from resilient material and in attaching the same to the flanges of the body and in forming a loop on said latch between said catch and the locality of attachment of said latch to one of said flanges.

Another object of the invention resides in providing the flanges of the body with oppositely disposed recesses and in forming the latch with ears adapted to enter said recesses and to hold the latch assembled relative to the body.

A feature of the invention resides in providing the latch with another loop between the ears thereof for urging said ears into said recesses.

Other objects of the invention reside in the

2

novel combination and arrangement of parts and in the details of construction hereinafter illustrated and/or described.

In the drawings:

Fig. 1 is a plan view of a clasp for bracelets illustrating the clasp in open position and drawn to an enlarged scale.

Fig. 2 is a side view of the structure shown in Fig. 1 with a portion of the body broken away.

Fig. 3 is a side view similar to Fig. 2 and showing the clasp closed, said view being drawn to a still greater scale.

Fig. 4 is a view similar to Fig. 3 with portions thereof broken away.

Fig. 5 is a perspective view of the clasp with portions of the same broken away.

Fig. 6 is a plan view of the latch of the invention.

Fig. 7 is a view similar to Fig. 6 showing a modified form of latch.

Clasps ordinarily used for bracelets have a latch operable from the face of the clasp and which readily are accidentally disengaged by coming in contact with various objects so that unintentional opening of the clasp frequently occurs. The instant invention overcomes this disadvantage by avoiding a construction in which the operating member for the latch projects laterally from the clasp.

My invention comprises a body 10 constructed of sheet metal and having a web 11 with flanges 12 and 13 extending outwardly therefrom. Pivotedly connected to one end of the body 10 is an inner link 14 which has eyes 15 and 16 at the ends of the same. A pintle 17 passes thru the eyes 15 and the flanges 12 and 13 and pivotally connects the link 14 to the body 10. In conjunction with link 14, an outer link 18 is employed which has a web 19 and flanges 21 and 22 extending outwardly therefrom. The link 18 is pivoted to the link 14 by means of a pintle 23 which extends through the eye 16 and through the flanges 21 and 22. The end of the link 18 has a fixed connector 24 on the same and to which one end of the bracelet 25 is attached. The other end of the bracelet is attached to an adjustable connector 26 which permits lengthening or shortening the bracelet to fit the wrist of the user. Such construction, forming no particular feature of the invention and being well known in the art, has not been shown in detail in the drawings. It will be noted that the body 10 and the links 14 and 18 are curved to fit the curvature of the wrist of the user. When the parts are folded to close the clasp, the flanges

21 and 22 lie adjacent the flanges 12 and 13 and are disposed within the same as best shown in Fig. 5.

For latching the clasp in closed position a latch 27 is employed which is shown in detail in Fig. 6. This latch is constructed of resilient sheet metal and is stamped to form longitudinally extending bars 28 and 29. The bars 28 and 29 have loops 31 and 32 at corresponding ends of the same which are connected to a reversely disposed loop 33. By means of this construction the bars 28 and 29 may be sprung together. On the bars 28 and 29 are formed ears 34 which are adapted to be received in recesses 35 in the flanges 12 and 13 of the body 10. The bars 28 and 29 are sprung together to force said ears into the recesses 35 and when received therein are held in position therein through the resiliency of the loops 31, 32 and 33. It will be noted that the latch 27 is disposed above the web 11 so that a space 36 is formed between said web and latch in which the connector 26 is movable.

Issuing outwardly from the bar 28 is a loop 37 which is connected to a reversely disposed loop 38. The end of this loop has issuing from it a transversely extending catch 39. The end of this catch has a finger piece 41 formed on it which is formed by merely enlarging the end of said catch and by means of which the catch may be manipulated. The loops 37 and 38 form resilient means accommodating movement of the catch 39 in a longitudinal direction.

The catch 39 projects through a bayonet slot 42 in the flange 12 of the body 10. This slot has a longitudinal leg 43 and a transverse leg 44 connected therewith. The leg 44 extends away from the web 11. The resilient means of the latch is so sprung that the catch 39 is urged toward the end of the leg 43. Also the catch 39 is bent out of the plane of the latch 27 so that said catch is urged toward the end of the leg 44. Thus when the catch 39 is manipulated by finger piece 41 and moved toward the leg 44, said catch springs into said leg and engages a shoulder 45 formed by the two legs 43 and 44. In such position, the catch is firmly held from movement by the resiliency of the resilient means of the latch 27.

For cooperation with the catch 39, the flange 21 of the link 18 is formed with a slot 46 which, when the clasp is closed, is adapted to register with the leg 43 of slot 42. The slot 46 is open at one end as indicated at 47 which is the end facing leg 44 of slot 42. This construction provides a hook 48 having a ledge 49 at the upper portion of the same and which is adapted to be engaged by the catch 39 to hold the latch in closed position.

The catch 39 is adapted to be automatically disengaged from the shoulder 45 and moved into a position to enter leg 43 of slot 42 when the parts of the clasp are brought into closed position. This is accomplished by means of a lug 51 formed on the flange 21 of link 18. The lug serves as an engaging member for engagement with the catch 39 and operates to disengage the lug 51 from said shoulder as the link 18 is moved toward the web 11 of body 10. As soon as said lug clears shoulder 45, the resilient means of the latch 27 urges the catch 39 along the leg 43 of slot 42 and toward the right as viewed in Fig. 1. The slot 46 being in register with leg 43 said catch enters slot 46 through the open end 47 thereof and springs back of the hook 48. The catch 39 may now engage the ledge 49 and serves to hold the clasp closed. In opening the clasp, finger piece 41 is merely moved into the

position shown in Fig. 1. Such movement disengages the same from hook 48 and the resiliency of the latch urges it into leg 44 where the same engages the shoulder 45 as previously described.

In Fig. 7 a modification of the latch is shown. The said latch greatly resembling the form shown in Fig. 6, the description of the similar parts will not be repeated and the same reference numerals preceded by the digit 1 will be used to designate the corresponding parts. In this form of the invention, a single loop 152 is used between the bars 128 and 129 instead of the three loops 31, 32 and 33 used with the other form of the invention. This permits of lengthening the loop 138 to give greater resiliency to the catch 139 when such added resiliency is desired.

The advantages of my invention are manifest. The latch can be constructed at an extremely low cost by stamping the same from resilient material. The latch is easily and quickly installed and is held in place through the resiliency of the material from which it is constructed. The cost of the body and links of the clasp is not increased. My improved latch extends laterally of the clasp and is hence not apt to become unintentionally disengaged by coming in contact with other objects. The catch must be manually manipulated to open the clasp and the clasp is easily closed by merely swinging the links into closing position. A broad surface is formed on the hook engaging the catch thereby requiring considerable movement of the catch to disengage the same.

Changes in the specific form of my invention, as herein described, may be made within the scope of what is claimed without departing from the spirit of my invention.

Having described my invention, what I claim as new and desire to protect by Letters Patent is:

1. In a clasp, a body having a web and a flange issuing outwardly therefrom, an inner link pivoted to one end of said body and adapted to overlie said web, an outer link pivoted to said inner link and adapted to overlie said inner link, said outer link having a flange adapted to be disposed adjacent the flange of said body, said flange of the body having a bayonet slot therein formed with a longitudinal leg and a transverse leg, a resilient latch anchored to said body and disposed between said web and inner link, said latch having a catch extending through said slot, said catch being urged for movement toward both ends of said slot and an engaging member on the flange of said outer link forming an open ended slot for the reception of said catch, said slot being adapted to register with the longitudinal leg of said bayonet slot when the clasp is closed, said catch when moved into the transverse leg of the bayonet slot engaging said shoulder and a lug on the flange of said outer link adapted to engage said catch and move the same out of engagement with said shoulder to release said catch for movement along the longitudinal leg of said bayonet slot and into the open ended slot of said link to latch the parts in closed position.

2. In a clasp, a body, a link pivotally connected thereto, said body and link when the clasp is closed having overlying parts, the part of said body being formed with a bayonet slot having a longitudinal leg and a transverse leg forming a shoulder therebetween and the other of said parts having an open ended slot adapted to register with the horizontal leg of said bayonet slot, a catch carried by said body and guided for movement along said bayonet slot, resilient means for urging said catch toward the end of said longi-

tudinal leg of said bayonet slot, said catch when moved into the transverse leg of said bayonet slot being yieldingly held in contact with said shoulder, and a lug on said link adapted to engage said catch to dislodge the same from said shoulder and move said catch into the longitudinal leg, said resilient means upon release of said catch moving the same along said longitudinal leg and into the open ended slot of said link to latch the parts in closed position.

3. In a clasp, a body, a link pivotally connected thereto, said body and link when the clasp is closed having overlying parts, a slot in one of said parts, an open ended slot in the other of said parts and adapted to register with one end of the slot in the other part, a catch movable in the first named slot and when in one end thereof clearing the part having the open ended slot and resilient means urging said catch toward the other end of the first named slot and into said open ended slot to latch the parts in closed position.

4. In a clasp, a body, a link pivotally connected thereto, said body and link when the clasp is closed having overlying parts, a slot in one of said parts, a ledge on the other part extending along a portion of said slot at one end thereof and facing away from said body when the clasp is in closed position, a catch movable in the slot and when in one end thereof clearing said ledge

and resilient means urging said catch toward the other end of said slot and into a position engageable with said ledge to hold the parts in closed position.

5. In a clasp, a body, a link pivotally connected thereto, said body and link when the clasp is closed having overlying parts, a slot in one of said parts, a ledge on the other part extending along a portion of said slot at one end thereof and facing away from said body when the clasp is in closed position, a catch movable in the slot and when in one end thereof clearing said ledge, resilient means urging said catch toward the other end of said slot and into a position engageable with said ledge to hold the parts in closed position, holding means for engagement with said latch to hold the same in the first named end of the slot and clear of said ledge and releasing means on the part having the ledge for disengaging said catch from said holding means upon closing of the clasp.
